ROTARY MIXING MACHINE

Filed April 14, 1930

UNITED STATES PATENT OFFICE

CONSTANT FORVILLE, OF SERAING, BELGIUM

ROTARY MIXING MACHINE

Application filed April 14, 1930, Serial No. 444,269, and in Belgium April 26, 1929.

The present invention relates to a rotary mixing machine from which the materials may be discharged while the machine works.

The various rotary mixing machines employed up to the present day do not allow of discharging the material they contain during the working of the machine. The stops and starts necessary for discharge purposes and the relative movement of the various elements of the mixing machine required for such stops and starts, have as consequence greatly to increase the wear and tear of said various elements and, therefore, of reducing the time during which the machine may be employed.

The object of the present invention is to construct a strong and simple machine allowing of working continuously therewith, i. e. without stops for discharging purposes. Such machine is applicable to all industries in which mixing of materials has to be effected and more particularly in the manufacture of concrete and mortar.

The machine according to the invention is formed of two vessels, keyed on one and the same shaft which is actuated to rotate, said vessels leaving between them a space, which may be closed by means of a ring adapted to slide on one of said vessels, the movement of said ring in one direction allowing the discharge of the material contained in the vessels without stopping the rotary movement of same.

The invention will be described hereafter with reference to the figures of the accompanying drawings, which illustrate, merely by way of example, an embodiment of the invention.

Fig. 1 is an elevation view of the rotary mixing machine;

Fig. 2 is a horizontal sectional view along the axial plane of the machine.

With reference to these figures, *a* designates the first vessel of the rotary mixer and *b* the second vessel, both said vessels being keyed

upon the shaft *f*, which is actuated to rotate by any suitable means. A ring *c* is mounted to slide on the vessel *a* and to close the space left between the two vessels *a* and *b* or to open same at will. This ring *c* is shown to be operated with a hand lever *e*, a set of transmission levers *d* and the transverse shaft *h*. The levers *d* are linked to a pair of swivelling arms, the free ends of which bear diametrically opposed rollers engaging an annular guide-way formed with two parallel ribs adapted to engage the outside on ring *c*. When the ring *c* is moved towards the left, the material contained in the vessels is discharged through the space uncovered between said two vessels. The ring *c* may be formed of one part or of a plurality of parts assembled to one another.

The material to be treated is fed into the mixing machine through the opening *g*, which is formed round and concentric with the shaft *f*. In order to preserve the driving shaft *f* against damage, protecting sleeves *i* have been arranged around it.

It is obvious that the motion of the ring *c* may also be obtained mechanically, any suitable mechanical or electrical motor being used to bring it about, either when operated or automatically.

It must be understood that the invention is not restricted to the form of construction hereabove described and illustrated, but that various modifications of construction may be brought thereto to suit the requirements, without departing from the scope of the invention.

I claim:

In a rotary mixing machine, the combination of a horizontal rotatable shaft, two bowl-shaped vessels facing one another and keyed on said shaft, a central feeding opening in one of said vessels, a ring space of constant width for discharging purposes between the edges of both bowl-shaped vessels, a cylindrical hoop slidably mounted on the outer

circumference of one of said bowl-shaped vessels, said hoop being movable parallel to the shaft and adapted to tightly abut against the front edge of the second one of said bowl-shaped vessels so as to tightly close said ring space, an annular guide-way on the outside of said hoop, two diametrically opposed rollers engaging said guide-way, a pair of swivelling arms carrying said rollers, a hand lever for 10 operating said swivelling arms, a transverse shaft carrying said hand lever, and means transmitting the oscillating movement of said transverse shaft to said swivelling arms.

In testimony whereof I signed hereunto my
15 name.

CONSTANT FORVILLE.
